CLAIM

The ornamental design for a vehicle hood assembly, as shown and described.

DESCRIPTION

FIG. 1 is a front, right perspective view of a vehicle hood assembly;

FIG. 2 is a front view thereof;

FIG. 3 is a leftside view thereof (where the rightside view is a mirror image of the leftside view); and,

FIG. 4 is a top view thereof.

The broken lines in the drawings illustrate portions of the vehicle hood assembly that form no part of the claimed design.
